Specification for Design.

Patented Oct. 11, 1921.

Application filed July 1, 1920. Serial No. 393,416. Term of patent 14 years.

To all whom it may concern:

Be it known that we, JOSEPH F. KELLER and FRANCIS J. BADGE, both citizens of the United States, and residents, respectively, of the city of New York, borough of Manhattan, and of the town of Woodhaven, borough of Queens, both in the State of New York, have invented a new, original, and ornamental Design for Circular Slide-Rules, of which the following is a specification, reference being had to the accompanying drawings, forming a part thereof.

Figure 1 is a plan view of one face of the circular slide rule, showing our new design.

Fig. 2 is an edge view and

Fig. 3 is a plan view showing the side opposite to the side shown in Fig. 1.

We claim:

The ornamental design for a circular slide rule substantially as shown and described.

JOSEPH F. KELLER.
FRANCIS J. BADGE.
